UNITED STATES PATENT OFFICE

RALPH F. SYMONDS, OF MARBLEHEAD, MASSACHUSETTS, ASSIGNOR TO NEW ENGLAND TRAWLER EQUIPMENT CO., OF EVERETT, MASSACHUSETTS, A CORPORATION OF MASSACHUSETTS

GALLOWS FRAME

Application filed July 5, 1928. Serial No. 290,459.

This invention relates to gallows frames of the type used on trawling vessels for handling and towing trawls.

Gallows frames are usually set-up on the deck of a trawler at either side near the rail and are adapted to be swung outboard to clear the rail when in use. Each frame carries an upper swivel block over which the towing warp or ground cable leads to the trawl and a lower sheave about which the cable is led to the bollards and the winch.

The duty imposed on gallows frames at sea and the strain upon them is severe. They are, moreover, subjected to destructive conditions of exposure which must be reckoned with in designing a frame which may be relied upon for long service. With these conditions in view, it is the object of the present invention to provide a gallows frame of a new and improved type, rigid and strong in construction and yet light enough to be handled conveniently. Consideration has also been given to the problem of mounting a gallows frame upon the deck of a vessel securely, eliminating all danger of its being carried away and at the same time permitting convenient detachment from its mounting when not in use. In this connection, an important feature of the invention consists in a hinged mounting for the gallows frame, so designed that when the frame is swung outboard and in use, the weight thereof and of the tackle and load is carried solidly by shoes or plates designed for the purpose, as distinguished from the hinge pin or bearings upon which the frame is carried at other times.

In one of its aspects, the present invention consists in a gallows frame embodying in its construction structural steel shapes of commercial channels and angle plates. Another feature of the invention, accordingly, consists in a gallows frame comprising a continuous channel iron bent to form two legs converging to a vertex from which the swivel block is suspended, and having cross girts secured in place between the legs of the frame and serving as a portion of the mounting of the frame.

These and other features of the invention

will be best understood and appreciated from the following description of a preferred embodiment thereof, selected for purposes of illustration and shown in the accompanying drawings, in which

Fig. 1 is a view of the gallows frame in front elevation;

Fig. 2 is a view in side elevation;

Fig. 3 is an inverted plan view; and

Fig. 4 is a view in side elevation, on a reduced scale, showing the gallows frame in position upon the deck of a vessel.

The main portion of the frame is formed of a continuous channel iron 10 shaped so that it comprises two legs converging to a curved vertex. Extending between the lower ends of the legs is a cross girt comprising two angle plates 14 with their flanges disposed outwardly. The connection is strengthened and the whole structure stiffened by corner plates 16, which are riveted to the flanges of the channel iron 10 and to the angle plates 14 of the cross girt. A curved reinforcing strap 12 extends over the vertex of the frame and is riveted to the web of the channel iron 10. A pair of transversely disposed angle plates 18 are riveted to the lower face of the cross girt angle plates 14 and the down-turned flange of each of these plates is tapered outwardly and provided at its deeper or wider end with a hole for the hinge pin or rod 20. Cooperating angle plates 22 are bolted to the deck of the vessel with their upwardly-extending flanges correspondingly tapered outwardly and in side surface contact with the downwardly-extending flanges of the angle plates 18. They are also provided with holes for the hinge pin 20 and thus constitute the stationary elements of a pair of spaced hinges having a common pintle in the rod or pin 20.

It will be apparent that the design of the hinge is such that the tapered lower edge of each angle plate flange on the gallows frame rests upon the web of the stationary angle plate 22 on the deck when the gallows frame is swung outwardly into operative position. Similarly, the tapering upper edge of the flange of each stationary or deck angle plate 22 rests upon the web of the movable angle

plate 18. In this way, a solid bearing and support of substantial area is provided for carrying the weight of the gallows frame and the load thereon when the latter is swung into its outboard position. When the gallows frame is swung inboard, as shown in Fig. 2, the hinge pin 20 has to carry only the weight of the frame.

A reinforcing plate 24 is riveted to the in-board side of the gallows frame at the vertex thereof, being shaped to the curved flange of the channel iron and provided with an outwardly-bent perforated tongue 26 which receives the clevis 28 of a stay rod 30. The plate 24 is provided with a pair of holes in its center section to receive the legs of a staple 32 which passes through a staple plate 34 disposed on the cutboard face of the gallows frame. The upper leg of the staple is notched into the web of the channel iron 10 and secured in place by nuts 36 upon its inner ends. The staple 32 is formed with an offset shoulder in its lower leg to hold the staple plate 34 in place and to reinforce it for carrying the swivel block 38. Chafing blocks 40 are riveted to the flanges of the channel iron 10 and have curved outer surfaces across which the cable may be drawn.

The members 14 of the cross girt carry cheek plates 42 between which is journaled the sheave 44. Both legs of the channel iron 10 are cut out in the web opposite the sheave 44, one opening 45 being shown in Fig. 2, to permit the passage of the cable 46 as it is led from the swivel block 38 to the bollards or winch.

It will be apparent from the foregoing description that the angle plates 22 constituting the stationary hinge members may be permanently bolted to the deck of the vessel and left there at all times without forming an objectionable structure. The gallows frame in its entirety may be connected to these hinge members by bringing the transverse angle plates 18 into registration with the stationary plates 22 and inserting the hinge rod 20. Nothing further is necessary beyond supporting the frame in position. This is effected, as shown in Fig. 4, by a strut or stay rod 30 connected at its upper end to the plate 24 and at its lower end to a bar 50, shown as pivotally mounted upon an angle plate post 52 secured to one side of the deck house 54 of the vessel. The lower end of the stay rod 30 is hooked into one of a series of perforations in the bar 50 which, with the stay rod, constitutes a toggle which may be straightened to move the gallows frame into outboard position, as shown in full lines in Fig. 4, or broken, as shown in dotted lines, to swing the gallows frame inboard. When the toggle is straightened and the gallows frame in operative position, it is desirable to provide an auxiliary tie bar 56 extending between the rear end of the bar 50 and the

rail of the vessel. When the bar 50 is swung into its upright position and the toggle broken to retract the gallows frame, the tie bar 56 may be detached and removed so as not to obstruct the deck.

The arrangement of the stay rod 30 is of secondary importance and may extend from the gallows frame directly to the opposite rail of the vessel or to the deck house, depending upon the location of the gallows frame. The plate 24 is provided with perforated ears to which supplementary stays may be attached, if desired. It will also be apparent that the cable 46 may be led from the sheave 44 in either direction and through either leg of the gallows frame. The general organization and assembly of the frame, therefore, affords a flexibility of set-up and range of usefulness which it is believed has not been hitherto approached in structures of this kind.

Having thus described my invention, what I claim as new and desire to secure by Letters Patent is:

1. A gallows frame comprising a continuous channel iron bent to form two legs converging to a curved vertex and having its flanges outwardly directed, a curved reinforcing strap extending over the vertex in contact with the web of the channel iron between its flanges, a swivel block suspended from the vertex, and a cross girt secured in place to and between the legs of the frame.

2. A gallows frame comprising a continuous channel iron bent to form upright legs merging into a curved vertex, a curved strap bolted to the web of the channel iron, a cross girt secured between the legs and forming therewith a self-contained rigid structure, and a hinged support for the frame whereby the latter may be swung about substantially the longitudinal axis of the cross girt.

3. A gallows frame for use on a vessel, comprising a rigid channel iron structure of substantially triangular shape, wedge-shaped hinge members disposed beneath the frame and secured to the base thereof and to the deck of the vessel, and a transverse hinge pin inserted through one end of said wedge-shaped members and adapted to support the frame when the latter is in substantially upright position while permitting the wedge-shaped members to support the frame when in an inclined hoisting position.

4. A gallows frame comprising a substantially triangular structure having an offset hinge connection at its base, and cooperating hinge members each having a supporting face oblique to the axis of the frame disposed beneath the latter and adapted to support it in an inclined hoisting position.

5. A gallows frame for use on a vessel comprising an elongated fabricated structure having a transversely extending base, a hinge connection disposed parallel to the base and offset with respect thereto, spaced tapering

hinge members secured beneath the base, and cooperating tapering hinge members secured to the deck of the vessel.

6. A gallows frame comprising an elongated fabricated structure having a transversely extending base, a pair of spaced wedge-shaped plates secured beneath said base in edgewise relation and perforated at their larger ends, a hinge pin extending between said plates and through said perforations, and similarly shaped wedge plates secured to the deck and carrying the hinge pin.

7. A gallows frame for use on a vessel, comprising an elongated fabricated structure, a hinge connection for securing said structure to the deck of the vessel and means located beneath the frame for supporting the weight of the structure adjacent to the hinge connection but offset with reference thereto.

8. A gallows frame for use on a vessel, comprising an elongated fabricated structure, a hinge pin for securing said structure to the deck arranged to carry the weight thereof when the latter is in substantially upright position, and supporting means for carrying the weight of the structure when the latter is in inclined hoisting position and for putting the hinge pin in a state of transverse tension.

9. A gallows frame comprising a substantially triangular structure fabricated of channel iron and having a curved vertex, a curved strap extending over the vertex and secured to the web of the channel iron, a U-bolt having its ends straddling said strap, and a swivel block suspended from said bolt.

10. A gallows frame for use on a vessel, comprising means for pivotally securing the base of the frame to the deck of the vessel, a truss rod extending from the top of the frame, an arm pivoted to the vessel and connected to the other end of the truss rod, the arm and rod forming a toggle which may be broken to move the frame into inoperative position and straightened to support the frame in an overhanging operative position.

11. A gallows frame comprising a continuous channel iron bent to form converging legs, a curved reinforcing strap extending over the vertex thereof, and a flat plate shaped to correspond in contour with the flange of the bent channel iron adjacent to the vertex, being rigidly secured thereto and having an ear perforated to receive the end of a stay member.

12. A gallows frame comprising a continuous channel iron bent to form two sides of a triangle, a swivel block suspended from the vertex thereof, a pair of spaced parallel angle plates secured between the ends of said bent channel iron, cheek pieces secured to the flanges thereof, and a sheave journaled between said cheek pieces and in cooperative relation to said swivel block.

13. A gallows frame for use on a trawling vessel, comprising a continuous channel iron bent to form converging legs, transverse angle irons connecting the lower ends of the legs and carrying a centrally disposed sheave, each leg being perforated near its end above the transverse angle irons, and a pulley block suspended from the vertex of the frame and adapted to receive a cable leading through the perforation in either leg.

14. A gallows frame for use on a vessel comprising a rigid triangular structure having a transverse base member, and angle irons secured to the deck of the vessel and said base member respectively, said irons being pivotally connected together and having edge faces extending a substantial distance outwardly away from the pivot connection, whereby, when the frame assumes an oblique operating position, the inclined edges will engage opposite flanges of said angle irons.
